GRINDING WHEELS

Arthur A. Miller, McHenry, Ill., assignor to Arthur A. Miller and Lou C. Casanov, Waukegan, Ill.

Application August 15, 1956, Serial No. 604,141

6 Claims. (Cl. 51—191)

My invention relates to improvements in grinding wheels.

My invention relates more particularly to a grinding wheel provided with an air cushioned tread portion.

Grinding wheels of the type to which this invention relates include a ring or band of abrasive such as sandpaper or the like mounted on the periphery or tread portion of the wheel, the tread portion being comparatively hard rubber, but so constructed that a certain amount of resiliency is given to the sanding surface of the wheel.

One of the principal objects of the present invention is to provide a relatively simple and inexpensive wheel of this sort that is made of a relatively small number of parts that are easily assembled to form a strong and sturdy device.

During the use of a sanding wheel, the wheel is caused to rotate at a relatively high velocity and the article to be sanded is applied against the sanding surface of the wheel. Due to the friction between the sanding surface of the wheel and the article applied thereto, there is a constant tendency for the abrasive band forming the surface of the wheel to creep or move circumferentially about the same. This movement is prevented in the device forming the subject matter of the present invention in a manner to be described hereinafter.

The principal object of the present invention is to provide an improved construction of grinding wheel having a tread portion capable of guided movement during expansion and provided with pin members adapted to move in elongated slots in the disc wheel members or plates in which the same is mounted.

A further object of the invention is to provide an improved construction of tread portion having a greater thickness or backing throughout the center of the same between the disc wheel or plate members, thereby providing a more efficient construction.

This application shows improvements over the construction of grinding wheels shown and described in my copending application, Serial No. 600,019, filed July 25, 1956.

Other objects and advantages will be more apparent from the following description wherein reference is had to the accompanying drawings, upon which:

Fig. 1 is a side elevational view of a grinding or abrasive wheel constructed in accordance with my invention;

Fig. 2 is a plan sectional view thereof, taken generally on the line 2—2 of Fig. 1 to show part of the grinding wheel in cross-section and a portion thereof in plan view;

Fig. 3 is a fragmentary cross-sectional view of an abrasive wheel of a larger size than that shown in Figs. 1 and 2 and constructed generally similar to the same.

In the embodiment of the invention which I have chosen to illustrate and describe the same, the grinding wheel 10 may be mounted upon the drive shaft 12 of an electric motor 14, the shaft 12 being screw-threaded at the end to receive a locking nut 16.

The grinding wheel may generally include a pair of mounting plates 18 and 20 similar to disc wheel members,

the plates having the openings 21 therein to receive the shaft 12. The mounting plates 18 and 20 are also provided with outwardly turned flanges at 22 and 24 so that the plates are spaced apart the thickness of a pair of side walls 26 and 28 of a rubber tread 30 which is fastened therebetween. Each of the flattened portions 18a and 20a of the mounting plates 18 and 20 is provided with a plurality of openings to receive the fastening bolts 32, the same passing through similar openings in the side walls 26 and 28 of the tread member 30 and the assembly being securely fastened together by means of lock nuts 34.

Each of the side walls 26 and 28 of the tread member is also provided with an outwardly projecting peripheral ridge 36 adapted to be received in a complementary peripheral groove 38 in the facing walls of each of the mounting plates 18 and 20.

The tread 30 which has the side walls 26 and 28 also has a peripheral or face flange 40 having a thickness sufficient to have a plurality of cross-pins 42 mounted therein, the cross-pins being adapted to extend beyond the edges of the tread member and engage in elongated openings 44 in the mounting plates 18 and 20. The peripheral tread portion 40 is also formed with an enlarged medial portion 40a spaced between the mounting plates 18 and 20, the side walls 26 and 28 also having an annular ridge 46 therein so that when the grinding wheel is subjected to a comparatively high rotational speed, centrifugal force will tend to swing out the tread portion 40 thereof to a slightly larger diameter, thus effectively tightening the abrasive band B on the same. At the same time, the outward thrust of the tread portion 40 of the grinding wheel is controlled in a radial direction by means of the pin members 42 that are guided in this movement in the elongated slots 44. Concentric rows of openings 48 and 50 may be formed in each of the mounting plates 18 and 20 so that heat generated in the rubber of the grinding wheel may be dissipated to atmosphere, thus giving the grinding wheel a longer life and making it more efficient in use.

In Figs. 1 and 2 I have shown a form of the invention in a comparatively small size; the grinding wheel shown is approximately 7 inches in diameter, and for grinding wheels of this size and upward this construction may be employed. However, for larger grinding wheels I prefer to employ the construction shown in Fig. 3 wherein the tread member 30 may have a portion of the facing surfaces of the side walls 26 and 28 vulcanized together as shown at V, and the tread may be provided with an air valve 70 communicating with the chamber 72 formed in the interior of the side walls 26, 28, and the peripheral facing tread portion 40.

With this construction, annular ridges 74 and 76 are provided in each of the side walls 26 and 28 of the tread member so that either from centrifugal force or by directly applied air pressure the peripheral surface of the tread member may be expanded to a larger diameter, the same again being controlled by the pin members 42 that extend into elongated slots 44 in each of the mounting plates 18 and 20. The mounting plates may also be provided with concentric rows of openings 80 for permitting heat generated in the rubber of the grinding wheel to be dissipated, as also shown in Figs. 1 and 2.

With the foregoing construction it can be seen that I have provided a highly improved construction of grinding wheel and one in which, by the use of the guide pins vulcanized in the rubber treads, the peripheral tread will also be held in place even though the sanding belt may become loose or broken in use. In addition, by the provision of more backing through the center of the tread portion, there will be less tendency in the starting for a backlash or swinging of the tread in the mounting plate.

While I have illustrated and described a specific embodiment,

ment of the invention, it will be apparent to those skilled in the art that changes and modifications may be made in the exact details shown and I do not wish to be limited in any particular; rather what I desire to secure and protect by Letters Patent of the United States is:

1. An abrasive wheel of the class described comprising a shaft, a pair of similarly shaped circular mounting plates secured together axially about said shaft and then flared outwardly, a rubber tread portion having side walls extending downwardly and positioned between said mounting plates, said side walls vulcanized together to form an air-tight chamber, an air valve associated therewith, each of said mounting plates having a circular groove therein and each of said side walls of said tread portion having a ridge engaging said groove, said tread portion having a flat circular edge and an abrasive band secured about its periphery, said mounting plates having a plurality of aligned elongated holes disposed about the periphery of the same and said tread portion having pin members extending therethrough and engaging said elongated holes.

2. An abrasive wheel of the class described comprising a shaft, a pair of similarly shaped mounting plates secured together and on said shaft, a tread portion having side walls extending downwardly and positioned between said mounting plates, each of said mounting plates having a circular groove therein and each of the side walls of said tread portion having a ridge engaging said groove, said tread portion having an abrasive band secured about its periphery, said mounting plates and side walls of said tread portion bolted together around said shaft within said circular ridge and groove fastening between the same.

3. An abrasive wheel of the class described comprising a shaft, a pair of similarly shaped circular mounting plates secured together axially about said shaft and then flared outwardly, a rubber tread portion having side walls extending downwardly and positioned between said mounting plates, said side walls vulcanized together to form an air-tight chamber, an air valve associated therewith, each of said mounting plates having a circular groove therein and each of said side walls of said tread portion having a ridge engaging said groove, said tread portion having an abrasive band secured about its periphery, said mounting plates having a plurality of aligned elongated holes disposed about the periphery of the same and said tread portion having pin members extending therethrough and engaging said elongated holes.

4. An abrasive wheel of the class described comprising a shaft, a pair of similarly shaped mounting plates secured together and on said shaft, said plates having outwardly turned curved portions terminating in parallel spaced alignment, a rubber tread portion having side walls extending downwardly and positioned between said mount-

ing plates, each of said mounting plates having a circular groove therein and each of said side walls of said tread portion having a ridge engaging said groove, said tread portion having a flat circular edge and an abrasive band secured about the same, the lower edges of said side walls of said tread portion being vulcanized together, said plates and side walls of said tread portion having a circular row of aligned holes therethrough within said ridge and groove connection and fastening bolts positioned through said aligned holes.

5. An abrasive wheel of the class described comprising a shaft, a pair of similarly shaped mounting plates secured together and on said shaft, said plates having outwardly turned curved portions terminating in parallel spaced alignment, a rubber tread portion having side walls extending downwardly and positioned between said mounting plates, each of said mounting plates having a circular groove therein and each of said side walls of said tread portion having a ridge engaging said groove, said tread portion having a flat circular edge and an abrasive band secured about the same, the lower edges of said side walls of said tread portion being vulcanized together, said plates and side walls of said tread portion having a circular row of aligned holes therethrough within said ridge and groove connection, and fastening bolts positioned through said aligned holes, the flat circular edge of said tread portion having transverse pin members extending therethrough and elongated holes in said mounting plates to receive the ends of said pin members.

6. An abrasive wheel of the class described comprising a shaft, a pair of similarly shaped mounting plates secured together and on said shaft, said plates having outwardly turned curved portions terminating in parallel spaced alignment, a rubber tread portion having side walls extending downwardly and positioned between said mounting plates, each of said mounting plates having a circular groove therein and each of said side walls of said tread portion having a ridge engaging said groove, said tread portion having a flat circular edge and an abrasive band secured about the same, the lower edges of said side walls of said tread portion being vulcanized together, said plates and side walls of said tread portion having a circular row of aligned holes therethrough within said ridge and groove connection and fastening bolts positioned through said aligned holes, the flat circular edge of said tread portion having transverse pin members extending therethrough and elongated holes in said mounting plates to receive the ends of said pin members, said flat circular edge of said tread portion having a medial inwardly extending bulge throughout its circumference.
